CLAIM

The ornamental design for ceiling light fixture diffuser side rail, as shown and described.

DESCRIPTION

FIG. 1 is a front perspective view of a ceiling light fixture diffuser side rail showing my new design; FIG. 2 is a rear perspective view thereof; and FIG. 3 is an end view thereof.

The end not shown is similar to the end shown. The side rail is broken away to indicate indeterminate length.

*Fig. 1.**Fig. 3.**Fig. 2.*
